(57) **CLAIM**

We claim the ornamental design for a flash for digital camera, as shown.

DESCRIPTION

FIG. 1 is a front/right-side/top perspective view of a flash for digital camera showing our new design;

FIG. 2 is a front-side elevational view thereof;

FIG. 3 is a rear-side elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a front/right-side/top perspective view thereof in association with a digital camera shown in broken lines for environmental reference.

The broken lines shown in the drawings depict environmental subject matter and form no part of the claimed design.
